UNITED STATES PATENT OFFICE.

WILLIAM J. KAUFFMAN, OF CLEVELAND, OHIO.

TYPE-WRITING MACHINE.

995,150.

Specification of Letters Patent. Patented June 13, 1911.

Application filed March 16, 1903. Serial No. 147,967.

To all whom it may concern:

Be it known that I, WILLIAM J. KAUFFMAN, of Cleveland, Cuyahoga county, Ohio, have invented a new and useful Type-Writing Machine, of which the following is a full, clear, and exact description, reference being had to the accompanying drawings, forming part of this specification, in which—

10 Figure 1 is an end elevation partly broken away illustrating the connections for moving the platen vertically; Fig. 2 is a cross-sectional detail of the upper portion of the mechanism; Fig. 3 is a partial bottom plan view; Fig. 4 is a central vertical section of the mechanism.

15 My invention relates to the class of type-writing machines and is designed to simplify and improve the mechanism for shifting the roller vertically.

20 In the drawings, 2 represents the carriage frame which is supported and moved in the usual way upon the slide-ways 3, 3. The vertical end supports 4, 4 of the carriage are 25 vertically slotted to receive vertically moving slides 5, 5, the lower ends of which are secured together by an intermediate connecting shaft 6, forming a frame in which the shaft 82 of the platen 66 is supported.

30 The lower ends of the slides 5 are provided with shallow curved recesses which rest upon a transverse shaft 7 extending across the machine below the carriage and supported upon links 8, 8 which project upwardly and are forted at their upper ends to engage circumferential recesses near the ends of the shaft 7 as shown.

35 In order to give a long uniform bearing for the platen frame I provide the entire 40 shaft 6 with a longitudinal bottom recess similar to those at the lower ends of the slides 5, thus giving a firm support for the platen in all positions. The links 8 are pivoted at their lower ends to horizontally 45 extending end levers 9, 9 which are rigidly secured to a rock-shaft 10 extending across the front of the machine above the key-levers.

50 In order to rock the shaft 10 and thus move the platen frame vertically I provide special keys at the ends of the bank, two of which at one end of the bank raise or lower the roller, while the two at the other end of the bank raise or lower and automatically 55 lock the roller in the adjusted position.

Referring to the right hand shifting

mechanism which is adapted to unlock and raise or lower the platen frame, and to lock it in the adjusted position, 11 is the lifting lever for elevating the roller and is pivoted 60 at its rear end to the key-lever shaft 12. A slide 13 is carried on this key-lever 11 by means of screws or pins 16, 16, the slide having at its front end a pin 14 which projects into a horizontal slot in the key-lever, 65 while the other end of the pin engages the face of a fixed cam plate 15. The upper part of this cam plate contains an inclined slot, while the lower part is curved on a radius whose center is substantially the fulcrum of the key lever. On depressing the lever 11, the engagement of the pin 14 with the curved surface of the fixed cam plate 15 will cause a forward sliding movement of the slide 13. The screws 16, 16 pass through 70 slots in the lever and are secured in the slide, and the rear end of the slide is provided with a small upwardly projecting hooked lug 17 which when the slide is drawn forwardly engages the upper side of a pin 80 or stud 18 secured to a lever arm 19, which is rigidly secured to a transverse rock-shaft 20. The shaft 20 is provided with a central forwardly projecting lever 21 (Fig. 4) having a loose pivotal connection at 22 with the 85 lever 23 secured to the rock-shaft 10. A lever-arm 24 is preferably integral with the lever 23, and carries an adjustable screw 24' engaging a plunger 25 which is acted upon 90 by a spring 26.

95 It is evident that when the lever 11 is depressed the slide acting upon the stud or pin 18 by means of its latch or lug 17 will rock the shaft 20 which in turn will rock the shaft 10 and thereby actuate and lift the levers 9 to lift the roller. The depressing lever A rocks on the shaft 20 and is similar to the lifting lever, except that its operating slide has an upwardly projecting lug with a flat upper face, which engages 100 the lower side of the stud or pin 18 and hence rocks the shaft 20 and thereby the shaft 10 in the opposite direction, thus depressing the carriage roller. In this connection, it will be explained that the slide 105 is cammed forward by a construction similar to 14, 15 of the lever 11.

110 The carriage roller is normally locked in its adjusted position and I provide for this purpose the catch-levers 27, each of which has in its upper portion three notches or recesses each adapted to engage an inwardly

projecting pin 28 on the link 8. The levers 27 at the opposite sides of the machine are pivotally connected to the frame of the machine by the screws 96. The downwardly projecting arm 29 of the lever 27 is provided with a rear cam face over which project the extended portions of the pins 94 on each of the lever-slides which move in the slots 94^a in the levers. As the key-lever is depressed, by the spring 26 acting upon the rock-shaft 10. The raising and depressing levers are kept in position and returned to normal position by means of a lever 30 which has two different fulcrums 34, 34, the one fulcrum being normally in contact with a lifting lever, and the other normally in contact with a depressing lever, on either of which it may swing; this lever 30 is supported by a pivotal connection with a rod or plunger 31 having an upper adjustable head 32 acted upon by a spiral spring 33 which exerts a constant lift thereon. The lever is provided at its ends with oppositely projecting pins 34, one of which engages the lifting lever, and the other the depressing lever. The locking levers are returned to their normal locking position whenever released by means of spring-pressed plungers 35 mounted in cylindrical cavities in the frames and pressed forward by springs 36. The third lever shown in Figs. 1 and 3 is one of a series of type bar levers and is fulcrumed upon the bar 12 at the rear of the machine. I provide locking levers at the right hand of the machine having recesses which allow these levers to be forced into locking position in any of the three different elevations; the levers at the other end are arranged to merely unlock and raise and lower, the platen frame being held in its adjusted position by the operator. When the carriage is locked in upper or lower position it may be restored to its normal intermediate position by striking a key arranged to unlock the catch and allow the platen frame to return to its normal position. It will be noted that instead of moving the platen frame vertically to adjust the position of the platen relatively to the type, I do not move the carriage itself, but only the paper carrying platen and its attachments. This gives a great advantage in ease of action and light touch compared with cases where the entire weight of the carriage is lifted.

In order to insure a parallel movement for the lifting shaft 7 I provide a special parallel motion mechanism therefor. I have shown this mechanism as consisting of two U-shaped arms 37 having their inner ends

rigidly secured to the ends of the shaft 7. The other ends of these U-shaped arms are pivoted to the frame preferably by means of curved lugs 38 having screw stems which are screwed into the outer curved portions 70 of the levers. These curved lugs fit in recesses in the end standards as shown in Fig. 2 and may be held in place by pins 39 engaging cam faces on the arms. Whenever the shaft 7 is moved vertically each end is 75 turned to exactly the same extent by reason of the levers 37, and the ends are thus compelled to move to the same extent in either direction. The arrangement of the parallel motion device may be varied as desired. 80 The curve of the outer face of the arm 37 is struck from the center of the shaft 7 as a radius, thus giving a true parallel motion to the shaft.

The advantages of my invention result 85 from the simplifying of the machine and reducing the number of parts; from the lifting of the platen without lifting the carriage, thus giving an easy action and in raising and lowering the roller. The mechanism for raising and lowering the carriage roller is simplified and a single spring device acts upon both of the shifting levers at either end of the back of keys.

I claim:—

1. A typewriting machine having a longitudinally movable carriage, said carriage having a vertical slot in each end thereof, a U-shaped platen frame, the ends of the platen frame being arranged to slide in the 100 slots in the carriage, a platen journaled in said frame, a rod mounted on the frame of the machine, said rod forming a support for the bottom bar of the platen frame, and means to raise and lower the rod to raise and 105 lower the platen frame and platen in the carriage; substantially as described.

2. A typewriting machine having a longitudinally movable carriage, said carriage having a vertical slot in each end thereof, a U-shaped platen frame, the ends of the platen frame being arranged to slide in the 110 slots in the carriage, a platen journaled in said frame, a pair of links pivoted to the frame of the machine, a rod mounted between said links, said rod forming the support for the bottom bar of the platen frame, and means to raise and lower the rod to raise and lower the platen frame in the carriage; substantially as described.

3. A typewriting machine having a longitudinally movable carriage, said carriage having a vertical slot in each end thereof, a U-shaped platen frame, the ends of the platen frame being arranged to slide in the 115 slots in the carriage, a platen journaled in said frame, a rod mounted on the frame of the machine, said rod forming a support for the bottom bar of the platen frame, means to raise and lower the rod to raise and lower the platen frame in the carriage; substantially as described.

the platen frame and platen in the carriage, and means to lock the carriage in its shifted position; substantially as described.

4. A typewriting machine having a longitudinally movable carriage, said carriage having a vertical slot in each end thereof, a U-shaped platen frame, the ends of the platen frame being arranged to slide in the slots in the carriage, a platen journaled in said frame, a rod having a groove mounted on the frame of the machine, the groove in

the rod forming a seat for the bottom bar of the platen frame, and means to raise and lower the rod to raise and lower the platen frame in the carriage.

15 In testimony whereof, I have hereunto set my hand.

WILLIAM J. KAUFFMAN.
